DESIGN FOR A DISPLAY STAND OR SIMILAR ARTICLE

Archie A. Struhl, East Orange, N. J.

Application January 31, 1948, Serial No. 144,188

Term of patent 7 years

(CL. D80—9)

To all whom it may concern:

Be it known that I, Archie A. Struhl, a citizen of the United States, residing at East Orange, in the county of Essex and State of New Jersey, have invented a new, original, and ornamental Design for a Display Stand or Similar Article, of which the following is a specification, reference being had to the accompanying drawing, forming part thereof.

In the drawing:

Fig. 1 is a front perspective view of a display stand or similar article, showing my new design;
Fig. 2 is a side elevational view thereof;
Fig. 3 is a top plan view; and
Fig. 4 is a cross-sectional view taken on line 4—4 of Fig. 2.

I claim:

The ornamental design for a display stand or similar article, as shown.

ARCHIE A. STRUHL.
